(57) **CLAIM**

The ornamental design for a gateway for industrial automation, as shown and described.

DESCRIPTION

FIG. 1 is a front view of a gateway for industrial automation in accordance with our new design, shown in a first environment;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front, top, right side perspective view thereof;

FIG. 8 is a front, bottom, left side perspective view thereof;

FIG. 9 is a front view of a gateway for industrial automation in accordance with our new design, shown in a second environment;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a front, top, right side perspective view thereof;

FIG. 16 is a front, bottom, left side perspective view thereof;

FIG. 17 is a front view of a gateway for industrial automation in accordance with our new design, shown in a third environment;

FIG. 18 is a rear view thereof;

FIG. 19 is a right side view thereof;

FIG. 20 is a left side view thereof;

FIG. 21 is a top view thereof;
